US00D825866S

(12) **United States Design Patent** (10) **Patent No.:** **US D825,866 S**
van Halder (45) **Date of Patent:** **** Aug. 14, 2018**

(54) **PET WASTE COLLECTOR**

(71) Applicant: **Josephus Johannes Maria van Halder**, Puyallup, WA (US)
(72) Inventor: **Josephus Johannes Maria van Halder**, Puyallup, WA (US)
(**) Term: **14 Years**
(21) Appl. No.: **29/474,646**
(22) Filed: **Dec. 9, 2014**
(51) LOC (11) Cl. **09-09**
(52) U.S. Cl. **USPC D30/162; D34/7**
(58) **Field of Classification Search**

USPC D34/1, 7, 11; D30/161, 162, 199; D6/512, 515, 518, 519; D3/203.5, 244, D3/201, 231, 243, 245, 251, 268, 290, D3/303; D9/702-711, 715-721, 761, D9/414, 433, 499, 416, 418, 420, 734; D24/121; 383/63, 42, 43, 93, 95, 97, 1, 383/21, 104, 121, 25, 14, 10, 61.2, 8; 604/385.02, 385.13, 358, 11, 359; 206/554, 440, 205, 438; 221/155; 229/175, 132; 294/1.3, 25, 1.5, 50.6, 294/176, 180, 58, 59; 15/227; 2/158; 493/194, 223, 226, 231, 235, 239, 346, 493/381

CLAIM

The ornamental design for a pet waste collector, as shown and described.

DESCRIPTION

FIG. 1 is a top view of a pet waste collector shown in a closed, folded flat configuration in which the scooper element is situated above the handle element;

FIG. 2 is a bottom view of the pet waste collector of FIG. 1;

FIG. 3 is a top view of the pet waste collector in an open flat

configuration shown with the connected handle and scooper;

FIG. 4 is a bottom view of the pet waste collector shown in

FIG. 3;

FIG. 5 is a rear perspective view of the pet waste collector in a first open expanded configuration and shown with the scooper being disconnected from the handle;

FIG. 6 is a front perspective view of the pet waste collector shown in FIG. 5;

FIG. 7 is a top view of the pet waste collector shown in FIG. 5;

FIG. 8 is a bottom view of the pet waste collector shown in FIG. 5;

FIG. 9 is a right side view of the pet waste collector shown in FIG. 5;

FIG. 10 is a left side view of the pet waste collector shown in FIG. 5;

FIG. 11 is a perspective view of the pet waste collector in a second open, expanded configuration; and,

FIG. 12 is a perspective view of the pet waste collector in a closed expanded configuration.
